DESIGN FOR A CARRIER FOR BOTTLES AND ANALOGOUS ARTICLES

Thomas D. Fisher, Jr., Tampa, and John S. Greeson, West Tampa, Fla.

Application June 24, 1941, Serial No. 101,650

Term of patent 3½ years

To all whom it may concern:

Be it known that we, Thomas D. Fisher, Jr., and John S. Greeson, citizens of the United States, residing at Tampa and West Tampa, respectively, in the county of Hillsborough and State of Florida, have invented a new, original, and ornamental Design for a Carrier for Bottles and Analogous Articles, of which the following is a specification, reference being had to the accompanying drawing, forming part thereof.

We claim:

The ornamental design for a carrier for bottles and analogous articles, as shown.

THOMAS D. FISHER, JR.
JOHN S. GREESON.
